(57) CLAIM

The ornamental design for an electrical connector, as shown and described.

DESCRIPTION

FIG. 1 is a front elevational view of an electrical connector, wherein the elements shown in dotted lines are for illustrative purpose only and form no part of the claimed design.

FIG. 2 is a top plan view thereof;

FIG. 3 is a bottom plan view thereof;

FIG. 4 is a rear elevational view thereof;

FIG. 5 is a left side elevational view thereof;

FIG. 6 is a front, top, and right side perspective view thereof, for illustrating a state in use thereof wherein the broken line showing of a memory card is for illustrative purpose only and forms no part of the claimed design.

FIG. 7 shows a front elevational view of the connector of FIG. 1 with the handle in a different position; and,

FIG. 8 shows a perspective view of the connector of FIG. 6 with the handle in a different position.

A right side elevational view of the electrical connector is omitted because it is presented symmetrical to the left side elevational view of FIG. 5.
